(57) **CLAIM**

The ornamental design for an envelope-shaped container, as shown and described.

DESCRIPTION

FIG. 1 is a perspective view of an envelope-shaped container showing our new design;

FIG. 2 is a front view of the container of FIG. 1.

FIG. 3 is a rear view of the container of FIG. 1.

FIG. 4 is a right side view of the container of FIG. 1.

FIG. 5 is a left side view of the container of FIG. 1.

FIG. 6 is a top view of the container of FIG. 1.

FIG. 7 is a bottom view of the container of FIG. 1.

FIG. 8 is a perspective of the container of FIG. 1 in an open position;

FIG. 9 is a perspective view of an alternate embodiment of the envelope-shaped container;

FIG. 10 is a front view of the container of FIG. 9.

FIG. 11 is a rear view of the container of FIG. 9.

FIG. 12 is a right side view of the container of FIG. 9.

FIG. 13 is a left side view of the container of FIG. 9.

FIG. 14 is a top view of the container of FIG. 9.

FIG. 15 is a bottom view of the container of FIG. 9; and,

FIG. 16 is a perspective view of the container of FIG. 9 in a open position.
